UNITED STATES PATENT OFFICE

109,584

DESIGN FOR A DRESS

Joseph Zinn, New York, N. Y.

Application April 8, 1938, Serial No. 76,367

Term of patent 3½ years

To all whom it may concern:

Be it known that I, Joseph Zinn, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress, showing my new design.

Fig. 2 is a rear view thereof.

I claim:

The ornamental design for a dress substantially as shown.

JOSEPH ZINN.
